COLLAPSIBLE STOVE
Russell O. Law, 2231 57th Ave.,
Oakland, Calif. 94605
Filed July 17, 1967, Ser. No. 653,877
8 Claims. (Cl. 126—262)

ABSTRACT OF THE DISCLOSURE

A single sheet of folded material having two leg portions and a perforated depressed center section. The sheet can be unfolded to engage and support a can of food and a heating element. 10

BACKGROUND OF THE INVENTION

Field of the invention

The present invention relates to portable stoves and more particularly it relates to a disposable portable stove which can be secured to the side or the bottom of a can for storage until use. 20

Description of the prior art

Although the prior art relating to portable and collapsible stoves has been carefully searched, no reference has been discovered which teaches a stove having the simplicity and disposable nature as herein disclosed. The closest prior art device which has been observed on the market is a small stove carrying the marking J. W. SPEAKER, Milwaukee, Wis., and entitled The Speaker Heatab-Cookit. This device is a small stove which can be folded into a rectangular box configuration having dimensions approximately 3" x 4" x 3/4". It has a generally flat perforated bed, or heating element platform, supported by two legs which are pivoted to each end of the flat bed. The legs can be rotated to lie parallel the flat bed or rotated perpendicular to the bed to form supports for a cooking vessel. The legs in conjunction with the flat bed form an H configuration with the two legs forming the vertical sides of the H and the flat bed forming the cross bar. The construction of this stove permits it to be folded into a box within which spare solid fuel heating tablets can be carried. 45

SUMMARY OF THE INVENTION

The present invention is a collapsible stove which comprises a single sheet of folded material having two leg portions and a depressed perforated center section disposed between the leg portions, the leg portions being foldable against the center section. The proportions of the stove, and its inherent structural configuration, permit it to be secured to a can of food for storage until use. When needed for heating the food, the stove can be removed from the can, unfolded, and engaged with the bottom of the can in the expanded, ready for use, form. 50

It is therefore an important object of the present invention to provide a disposable cooking stove which can be secured to a can of food until needed.

It is another object of the present invention to provide a collapsible cooking stove which can be secured either to the side of a cylindrical can or to a flat end or side thereof. 60

It is a further object of the present invention to provide a stove which is small in size and which, when unfolded 65

2

for use, actually engages with the bottom of a can when arranged for heating it.

It is yet another object of the present invention to provide a cooking stove which could be disposed within a false bottom of a can of food along with one or more solid fuel heating tablets. 5

And still a further object of the present invention is to provide a collapsible stove which engages with the bottom of a can of food so that the can may be hand held during warming of the food.

DESCRIPTION OF THE DRAWINGS

FIGURE 1 is a side elevation of a can having a collapsible stove secured to a cylindrical side thereof;

FIGURE 2 is a cross-sectional view taken along lines 2—2 of FIGURE 1;

FIGURE 3 is a side elevational view of a collapsible stove of the present invention engaged with and supporting a can of food for heating;

FIGURE 4 is a bottom elevational view of FIGURE 3 showing the engagement of the stove with the can;

FIGURE 5 is a plan view of a collapsible stove of the present invention secured to the flat end of a can of food;

FIGURE 6 is a sectional view taken along line 6—6 of FIGURE 5;

FIGURE 7 is a side elevational view of a can of food supported by the collapsible stove of FIGURES 5 and 6;

FIGURE 8 is a bottom elevational view of the stove of FIGURE 7; and

FIGURE 9 is a side elevational view in section showing an alternative embodiment for securing a collapsible stove to a can of food within a false cover. 30

DESCRIPTION OF THE PREFERRED EMBODIMENT

Reference to FIGURES 1—4 of the drawings will aid in understanding the first preferred embodiment of the present invention. There shown is a collapsible stove 11 which is made from a single sheet of folded material, preferably metal. A stove can be stamped, perforated, and folded in a relatively simple operation from a flat sheet of pliable material on the order of thickness of the material used in large food cans. 35

The stove is formed with a pair of planar leg portions 13 and a perforated depressed center section 15 disposed between the leg portions. In both contemplated embodiments of the stove, the leg portions are foldable against or alongside the depressed or concave center section. In the embodiment of FIGURES 1—4, the depressed center section 15 of the stove has a generally cylindrical curvature which conforms to the outer configuration of the can 17 to which the stove is or can be secured. Different size stoves are used for different size cans and are proportional in size. 50

The two leg portions are folded for securement to the can (FIGURES 1 and 2) by bending them into a cylindrical configuration which fits adjacent or around the depressed center section of the stove. The leg portions are folded around the center section so that the stove can be secured to a can by various means such as a strap 19, or by a label of the can, or by some sort of adhesive or other means. 55

To use the stove, it is simply necessary to remove it from the can and to bend the two leg portions away from the depressed center section until they are relatively 60

parallel and project downward from their connection (simply a fold in the material) with the center section. The length and width of each stove must be made to such proportions that when it is compressed by moving the two legs toward each other in parallel relationship, the upper four corners 21 of the stove will fit within the projecting rim 23 of the unopened end of the can (FIGURES 3 and 4). The pressure on the legs is released and the stove expands so that the corners thereof bear against the rim with spring pressure. This provides a relatively secure engagement of the stove with most of the types of cans presently used by the canning industry.

The stove can be readied for use simply by separating the stove from the can, unfolding it, engaging the stove with the bottom of the can, inserting the solid fuel tablet 25 on the depressed center section, and setting the assembly on a level surface. The stove can even be used indoors or set upon a burnable surface and lighted without adverse effect because the stove supports the burning fuel at an insulating distance from the surface.

A combustible solid fuel heating composition or tablet 25 is disposed upon the perforated portion of the depressed center section of the stove under the center of the can. The perforations and the curvature of the depressed surface permit good circulation of air for excellent combustion of the solid fuel element. It has been found that the curvature or concavity of the depressed center section of the stove supports the heating tablet in such a manner as to permit circulation of air under the tablet if the tablets are of the cylindrical type and are placed with a flat end downward. This provides better combustion than is obtainable with the cited prior art wherein the tablet is placed on a flat surface which prevents circulation of air under the tablet. A multiplicity of tablets can be used for larger sized cans to provide increased heating capacity.

After the food has been heated, a knife or other eating utensil may be inserted between the can and the stove and the stove easily pried off the bottom of the can and disposed of when it is convenient to do so.

The embodiment of the invention shown by FIGURES 5-9 relates to a stove which can be secured to the flat end 27 of a can (FIGURES 5, 6 and 9) as opposed to the previously described embodiment of FIGURES 1-4 wherein the stove is mounted on the cylindrical surface of the can. The second embodiment of the collapsible stove is also made from a single sheet of folded material having two leg portions 29 and a perforated depressed center section 31 disposed between the leg portions. However, the depressed center section is V shaped instead of cylindrical. The leg portions are foldable against the center section as with the first embodiment.

The center section is formed of two planar sections 33 connected at their upper edges by folds in the material to the upper ends of the legs and the two planar sections are interconnected to each other by a fold in the material at the bottom of the center section. A cylindrical pellet 35 is placed therein on its side so that it does not slip and have a flat end blanked against a planar side of the center section.

The leg portions and the two planar center sections can be collapsed accordion-like into a generally flat configuration for securing to the flat end of the can. The stove can be secured to the can by means of a strap as shown in FIGURE 5 or it can be secured in a false bottom 37 of some type, one of which is shown in FIGURE 9. A false bottom could be made with enough space or height to contain one or more solid fuel heating tablets.

As with the first embodiment, the size and proportions of a stove having a V shaped center section are dependent upon the size of the can the stove is used for heating. In each case, it is advantageous if the stove is proportioned so that the four upper corners 39 engage the rim 41 of the unopened end of the can. The height of the legs are determined by the proportions selected for mounting the folded stoves on the ends or sides of the cans.

The present invention also contemplates a combination food container, cooking vessel and cooking stove which includes a cylindrical can of food having a removable end cover, either end of the standard can, and a collapsible stove which is formed from a single sheet of folded material and has two leg portions and a perforated center section having either a generally cylindrical curvature as described in the embodiment shown in FIGURES 1-4 or the V shaped configuration as shown in FIGURES 5-9. The first described embodiment of the stove can be secured to the cylindrical surface of a can with the leg portions folded adjacent and around the center section while the second embodiment of the stove can be secured to the flat end of a can with the legs and center section folded accordion-like to a flat configuration.

The present invention provides a unique advantage not found in any other heating stoves which have been observed in the prior art. This is the capability of the stove to be secured to the bottom of the can so that during heating of the can, the can may be held in the hand of the cook or consumer. In other words, it is not necessary to set the stove down during heating or to remove the stove when the contents are being consumed. The stove maintains the proper relation and distance between the fuel heating element and the bottom of the can at all times and keeps the food warm during the meal. As the solid fuel element burns, a very small amount of residue or sweating occurs on most heating tablets. This tends to secure the heating element in position on the depressed surface of the stove and decreases the sensitivity of the stove to its attitude or how it is handled by the person holding the can.

It thus will be seen that the present invention provides a relatively inexpensive and completely disposable collapsible cooking stove which can be secured to a can of food having either cylindrical sides or a flat end.

It will be apparent from the foregoing description of the invention in its preferred form that it will fulfill all of the objects attributable thereto. While it has been illustrated and described in considerable detail, the invention is not to be limited to such details as have been set forth except as may be necessitated by the appended claims.

I claim:

1. A collapsible stove comprising a single sheet of folded material having two leg portions and a perforated depressed center section disposed between said leg portions said leg portions being foldable adjacent said center section for securing to the outer surface of a can.
2. The center section of claim 1 wherein said stoves are expandable to engage one end of a can.
3. The collapsible stove of claim 1 wherein said center section has a generally cylindrical curvature and said leg portions can be folded around said center section so that said stove can be secured to the side of a cylindrical can.
4. The collapsible stove of claim 1 wherein said center section is V shaped whereby said leg portions and the center section can be collapsed accordion-like into a generally flat configuration for securing to a flat end of a can.
5. The center section of claim 4 wherein said center section is formed of two planar sections connected at their upper edges to the upper ends of said legs and said planar sections are interconnected to each other at the bottom of the depressed center section.
6. A combination food container, cooking vessel, and cooking stove comprising a cylindrical can of food having a removable end cover, and a collapsible stove being formed from a single sheet of folded material having a pair of planar leg portions and a perforated and depressed center section having a generally cylindrical curvature disposed between said leg portions, said stove being removably secured to the cylindrical surface of said can with said

- leg portions being foldable adjacent and around said center section.
7. A combination food container, cooking vessel, and cooking stove comprising
- a can of food having a flat end and a removable end 5 cover, and
  - a collapsible stove being formed from a single sheet of folded material having a pair of planar leg portions and a perforated and V shaped depressed center section disposed between said leg portions, said leg portions and said planar center sections being foldable 10 accordion-like into a generally flat configuration and

- removably secured adjacent a flat end of said can.
8. The collapsible stove of claim 7 wherein a cover is secured to the flat end of said can enclosing said stove in a false bottom to said can.
